UNITED STATES PATENT OFFICE.

DELOS E. HAMMER, OF HIGH POINT, NORTH CAROLINA.

TYPE-WRITER ATTACHMENT.

1,252,265.

Specification of Letters Patent.

Patented Jan. 1, 1918.

Application filed October 13, 1916. Serial No. 125,474.

To all whom it may concern:

Be it known that I, DELOS E. HAMMER, a citizen of the United States, residing at High Point, in the county of Guilford and 5 State of North Carolina, have invented new and useful Improvements in Type-Writer Attachments, of which the following is a specification.

This invention relates to an improved 10 copy holder for typewriters and is designed to provide means whereby the lines of the copy will be properly spaced and also whereby, when the spacer member is brought to the lowermost line of the copy, the device 15 may be actuated to turn the page of the copy book and return the spacer to the first line to be copied from the adjacent page of the said copy holder.

In carrying out my invention it is my 20 purpose to construct a device of this character which may be easily and quickly connected to the typewriting machine and easily and quickly operated by the typist.

It is also my purpose to produce a device 25 of this character which shall embody the desirable features of simplicity, efficiency and accuracy.

With the above and other objects in view 30 the improvement resides in the construction, combination and arrangement of parts set forth in the following specification and falling within the scope of the appended claims.

In the drawings:

Figure 1 is a side elevation illustrating 35 the arrangement of the improvement upon a typewriter,

Fig. 2 is a rear view of the same,

Fig. 3 is a vertical sectional view approximately on the line 3—3 of Fig. 2,

0 Fig. 4 is a top plan view,

Fig. 5 is a sectional view substantially similar to Fig. 3 but illustrating the table folded rearwardly of the typewriter,

Fig. 6 is an enlarged sectional view 45 through the spacer bar, and

Figs. 7 to 9 illustrate details.

The improvement may include a flat base 1, and if desired the typewriter machine 2 may rest upon this base, the said base extending rearwardly of the machine. Rising 50 from the base adjacent to the rear thereof is a plurality of uprights 3, the end uprights being spaced from each other a distance approximately equaling the depth of the machine 2.

Journaled upon certain of the uprights 3

adjacent to the top and bottom thereof are shafts 5 and 6 respectively. The shaft 6 has secured thereto a toothed or ratchet wheel 7 which is arranged outwardly of one of the 60 end uprights 3, while upon the said shaft inward of the referred to end upright is a grooved wheel 8. The shaft 5 has secured thereon a grooved wheel 9, and upon the periphery of this wheel is wound and secured 65 a belt or flexible member 10 which is also wound around and secured to the wheel 8. Upon the referred to end upright 3, beyond which the toothed or ratchet wheel 7 is arranged, I pivotally secure, as at 11, a 70 spring member in the nature of a dog 12, the said dog co-acting with the teeth of the wheel 7. Upon the base 1 I arrange in suitable bearings 13—13, a longitudinally disposed operating rod 14, the same having its 75 outer end provided with a knob or handle 15 and its inner end engages with one of the teeth of the wheel 7 whereby when the rod is moved longitudinally in the direction of the wheel, the said wheel will be rotated and 80 consequently turn the shaft 6 to actuate the belt 10 and revolve the wheel 9, the purpose of which arrangement will presently be described.

Upon the rod 14, and disposed adjacent 85 one of the bearings 13 for the said rod I arrange an adjustable stop member 16 which, when contacting with the said bearing 13, will limit the longitudinal movement of the rod in the direction of the wheel 7. 90

The rod 14 is provided with an offset member or lug 17 and the said rod between the lug 17 and the inner bearing member 13 has arranged thereon a helical spring 18, one end of the said spring being secured to 95 the lug 17 and the other end bearing against or if desired secured to the bearing member 13. The spring 18 normally moves the rod a predetermined distance in an outward direction so that its engaging end will not 100 forcibly contact with the teeth of the wheel 7, while the inward movement of the rod, in a direction for turning the wheel 7, is limited by the stop member 16, as previously set forth.

The lug member 17 is provided with an opening through which passes a rod member 19 that has its outer end provided with a head 20 and its inner end secured to the spring dog 12, as illustrated by the drawings. The base 1, to the rear of the ratchet wheel 7, has arranged thereon spaced plates 110

21 and 22 respectively, the plate 22 having its upper face beveled and extending longitudinally along the sides thereof is a spring strap 23, the same comprising a curved or 5 arch-shaped member and adapted to have its end received in the notch or space between the plates 21 and 22 when the rod member 14 is pulled outwardly to bring the end thereof out of engagement with the 10 teeth of the ratchet wheel 7 to cause the lugs 17 to contact with the head 20 of the member 19 to release the dog 12, the purpose of which arrangement will presently be apparent.

15 Secured upon the shaft 5 is a grooved wheel 24 and extending horizontally from the frame provided by the uprights 3 at a suitable distance above the typewriter is a supporting member 25. Through this member 25 passes a pivot 26 and this pivot has journaled thereon one or more segmental tooth racks 27, the said racks being engaged by spring pressed dogs 28 and the said racks support the table 29 upon which the copy 20 is adapted to rest. As shown in Fig. 7 of the drawings, the spring pressed dog 28 is provided with an operating handle 28', whereby the dog may be swung out of engagement with the toothed segment 27 to 30 permit of the angular adjustment of the table 29 with respect to the members 26 and to the standards 3.

The spacer member which works upon the outer face of the table is indicated by 35 the numeral 30 and comprises an element shaped to include a flat underface 31, a rear face 32 which is preferably slightly rounded, the said face 32 being provided with a facing or coating of some suitable 40 compressible material, such as rubber, which is indicated by the numeral 33 and if desired the face 32 may be provided with slight projections in the nature of pointed elements. The outer face of the spacer member 45 31 is rounded, as indicated by the numeral 34, and said member 34 at spaced intervals is provided with depressions or sockets 35 through which pass pivot members 36 whereby to connect the widened ends 37 of 50 substantially arch shaped members 38 to the spacer 30. A transversely disposed member 40 connects the rear ends of the members 38. The central member 39 has secured thereto a flexible element 41 which is wound 55 around the wheel 24 and which has its ends provided with a weighted member 42.

Pivotedly secured, as at 43, to the base 1 is a lever 44. This is disposed at an angle from its outer end to its pivot 43 as indicated by the numeral 45, and if desired the straight end of the lever may be retained between the plates 21 and 22 through the medium of a spring 46 exerting a pressure between the base and the angular end of the 60 lever. The angular end of the lever is

disposed in the path of contact with the weight 42, and the operation of the device may be briefly described as follows: The book or tablet is arranged upon the table 29 so that the spacer member is disposed over the outer page thereof. The spacer member is moved to the top of the table when a pressure upon the handle 15 will rotate the ratchet wheel 7 and consequently the shaft 6 draws the belt 10 around the wheel 8 causing the wheel 9 to be revolved and as a consequence permitting the weighted spacer member to gravitate over the inclined table toward the outer end thereof, the movement of the spacer being regulated by the element 16 connected with the rod. When the spacer member has been moved to the end of the copy book or tablet upon the table, the operator pulls the rod 14 outwardly and in so doing draws the member 19 to bring the dog 12 out of engagement with the teeth of the ratchet wheel and the member 23 is arranged within the notch or space between the plates 21 and 22 and over the straight end of the lever 44. It is 70 to be understood that the weight 42 is heavier than the combined weight of the frame provided by the members 38 and 40 and the spacer 31 so that when the parts are released as just described the weight will 75 travel over the wheel 24 drawing the spacer upwardly of the table. By reason of the peculiar formation of the ends of the member 38 and their pivotal engagement in the notches provided upon the outer face of 80 the spacer member 31 and also in consideration of the rounded corner between the curved face 32 and the flat face 31 of the said spacer. A movement of the spacer in a rearward direction will cause the same to 85 be swung to bring its flat face 31 out of engagement with the copy and its compressible face 33 over the copy. The sharpened members, indicated by the numerals 47, upon the face 33 will engage with a page of the copy 90 moving the same inwardly over the rear edge of the table 1 and so folding the used page of the copy over the back of the table. When the parts are brought to this position the weight 42 will contact with the angular 95 end 45 of the member 44 swinging the same upon its pivot and bringing the member 23 from between the plates 21 and 22, permitting the spring 18 to exert a tension and force the rod rearwardly or in the direction 100 of the ratchet wheel 7, whereby the spring dog 12 will again engage with the ratchet wheel to prevent the turning of the ratchet wheel in a retrograde direction.

If desired one of the members 38 or the 105 connecting bar or rod 40 may be provided with a straight extension 49 which passes through a slot 50 formed upon a member 51 that is secured to the frame formed by the uprights 3, and by this arrangement it 110

will be noted that the spacer bar will be at all times properly arranged upon the table or upon the copy arranged upon the table. It will be also noted that by providing the 5 toothed segments in the spring dogs operated by the member 31, the table 29 may be swung upwardly of the typewriting machine, to permit of the operator properly arranging the paper in the machine.

10 From the above description, taken in connection with the accompanying drawings, the simplicity of the device, as well as the advantages thereof will, it is thought, be perfectly apparent to those skilled in the 15 art to which such invention appertains without further detailed description.

Having thus described the invention, what I claim is:

1. In a device for the purpose set forth, 20 a support, a table carried by said support, means for adjusting the table angularly with respect to the support, a pivoted gravitating spacer bar movable over the table and including a straight surface and an angular friction surface, means, including mechanism, connected with the spacer bar designed, when actuated, to permit of the 25 said spacer bar gravitating in a step by step movement toward the lower end of the table, means for returning the spacer bar to its initial position, and said spacer bar designed by virtue of its contact with the table to turn upon its pivot to bring the frictional 30 surface thereof over the said table, when 35 the said spacer is returned to its said initial position.

2. In a device for the purpose set forth, standards, shafts journaled in bearings in 40 said standards, wheels upon said shafts, a ratchet wheel upon one of said shafts, a spring pressed dog normally engaging with the ratchet wheel, a longitudinally movable bar disposed to engage with the ratchet 45 wheel to rotate the same, a belt member secured to two of the alining wheels upon the shafts, a flexible element trained over the other wheel upon the shaft, a weight upon the end of the said flexible member, a table 50 pivotally connected with the supports, means for maintaining the table at an angle with relation to the support, a spacer bar 55 arranged upon the table, and a connection between the spacer bar and the flexible element.

55 3. A line spacer for copy books or the like, including an inclined table upon which the book is designed to rest, a pivoted spacer member designed to gravitate over the book toward the outer end of the table, said 60 spacer including a flat surface arranged to rest upon the book, when the said spacer gravitates over the book, and an angular friction surface designed, by virtue of a 65 contact of the spacer with the book to be brought to engage with the page of the book,

when the spacer is swung upon its pivot by virtue of the retrograde movement thereof, means, comprising mechanism, and including a flexible element connected with the spacer, whereby to permit the gravitating 70 of the spacer over the book and table, and means associated with said operating means, for returning the spacer to its initial position.

4. A line spacer for copy books for type- 75 writing machines or the like including a support, a table pivotally secured to the support and disposed over the machine, means for sustaining the table at a desired angle with relation to the machine, said table adapted to support the copybook, a line spacer adapted to be positioned over a page of the copy book, a flexible member connected with the spacer, means for operating the flexible member, to permit of the 80 spacer gravitating downwardly on the table, said spacer including a pivoted member having a flat surface and an angular round roughened surface, and said flat surface designed to rest on the page of the book 85 when the spacer gravitates over said page, and means comprising mechanism connected with said spacer designed to return the spacer to its uppermost position after the same has gravitated to the bottom of the 90 page of the book, and by virtue of the frictional engagement of the said spacer with the said page of the book, to cause the said spacer to turn upon its pivot to bring its roughened surface over the said page 95 of the book, as and for the purpose set forth.

5. A line spacer for stenographers' notebooks, including a support, a pivoted table on said support, means between said support and table for holding the table at an angle 100 with respect to the support, upper and lower shafts on the support, oppositely spaced, grooved wheels on said shafts, a flexible element wound around said wheels and secured thereto, a ratchet wheel on the lower 105 shaft, a spring dog normally engaging said wheel, an operating rod for said wheel, arched arms arranged over the table, a spacer bar pivotally secured to said arms, and said spacer bar including a flat surface 110 and an inner rounded and serrated surface, a member connecting said arms, a roller on the upper shaft, a flexible element wound therearound and connected to one of the arched arms, and a weighted member upon 115 the free end of said flexible element, all as and for the purpose set forth.

6. In a line spacer for copy books, standards, an angular support on said standards, a toothed segment pivoted thereto, a table 120 carried by said segment, a spring pressed dog upon the support engaging with said segment, operating means for said dog, upper and lower shafts journaled in the standards, grooved wheels on said shafts, a 125 130

4

flexible element wound around said wheels and secured thereto, a ratchet wheel on the lower shaft, a spring pressed dog co-acting therewith, a headed operating handle for said dog, a spring pressed operating rod for actuating said ratchet, means between said rod and the referred to rod for the dog, whereby to move the dog out of engagement with the ratchet when the operating rod is moved out 10 of contacting engagement with the ratchet, arcuate arms having enlarged ends presenting angular surfaces, a spacer bar having sockets, the inner walls of which being angular receiving the said ends of the said 15 arms, pivot members connecting the arms to the spacer, said spacer including a flat surface and an inner round surface which is serrated, a connecting member for the arms, a second grooved wheel on the upper shaft, a flexible element wound therearound and connected with the arms, a weight on 20 the free end of said flexible element, a slotted member connected with the standards, and a guide member for the arms of the spacer passing through said slot, all as 25 and for the purpose set forth.

7. In a spacer for copy books, a base, standards arising therefrom, an angular member on said standards, a toothed segment pivoted thereto, a table secured to said 30 segment, a spring pressed dog engaging the teeth of the segment, an operating handle therefor, spaced shafts journaled in bearings adjacent the upper and lower ends of

the standards, oppositely disposed, grooved 35 wheels on said shafts, a flexible element wound around said wheels and secured thereto, a ratchet wheel on the lower shaft, a spring pressed dog engaging said wheel, a headed rod connected to said dog, a spring 40 pressed operating rod for said ratchet, means for limiting the movement of the rod in the direction of the ratchet, means between said rod and the rod connected with the dog, whereby to move the last mentioned 45 rod to bring the dog out of engagement with the ratchet, when the operating rod is moved from said engagement, means for retaining both of said rods in such last mentioned positions, a spacer bar arranged over the 50 table, arms pivotally connected therewith, guide means between the standards and said arms, a second grooved wheel on the upper shaft, a flexible element wound around said wheel and having one of its ends connected 55 with the arms, a weight on the free end of said flexible element, and said weight being in the path of contact with the rod retarding means designed to contact with such means, when the weight is permitted to 60 descend, to actuate the same and permit of the movement of both of the rods in the direction of the ratchet wheel, and whereby to again bring the spring dog into contacting relation with said ratchet wheel. 65

In testimony whereof I affix my signature.

DELOS E. HAMMER.
